UNITED STATES PATENT OFFICE.

ANDREW RUNSTETLER AND MICHAEL RUNSTETLER, OF DAYTON, OHIO,
ASSIGNORS TO THE FARMERS FRIEND MANUFACTURING COMPANY, OF
SAME PLACE.

GRAIN-DRILL.

SPECIFICATION forming part of Letters Patent No. 285,363, dated September 18, 1883.

Application filed May 26, 1883. (No model.)

To all whom it may concern:

Be it known that we, ANDREW RUNSTETLER and MICHAEL RUNSTETLER, citizens of the United States, residing at Dayton, in the 5 county of Montgomery and State of Ohio, have invented new and useful Improvements in Grain-Drills, of which the following is a specification.

Our invention relates to grain-drills, and 10 may be applied to seeding-machines of any class in which hoes are employed for conducting the grain to the earth, as well as to cultivators for covering the grain with soil where sown broadcast.

15 It is the object of our invention to provide simple and effective mechanism for shifting the hoes or drill-boots from a single into a double rank, or vice versa, and automatically locking them in either position, or, if desired, 20 reciprocating the hoes continuously; secondly, to provide mechanism whereby the hoes or boots may be raised from or lowered to the ground, and securely locked in either position without regard to their arrangement in a single 25 or double rank; thirdly, to provide a seat for grain-drills which may be longitudinally adjusted upon the frame or wholly removed therefrom, having a foot-rest for the driver, which forms part of the attaching and adjusting devices.

30 To these several ends our invention consists, for the first part, in a series of hoes or drill-boots attached to a corresponding series of drag-bars, the latter being connected alter-

35 nately to one or the other of two transverse rock-bars having segment-gears at their extremities meshing together, a connecting-rod pivoted to an arm on one of said rock-bars, and driven by a pinion which is normally held 40 out of engagement with an actuating-gear upon the axle, a notched or slotted flange or bearing-cylinder upon said pinion, riding upon a toothed support rigidly mounted upon the frame, and a spring-actuated lever, in one ex-

45 tremity of which the pinion is journaled, whereby the pinion is raised to mesh with the actuating-gear, the locking-tooth is withdrawn from the slotted flange, and the latter caused to ride upon the toothed support until the

shifting of the hoes is completed, when a second notch in the flange engages with the toothed support, being automatically thrown into locking-engagement therewith, and the pinion at the same time withdrawn from its actuating-gear by the spring-actuated lever. 50

55 Our invention consists, for the second part, in a series of hoes or drill-boots attached to a corresponding series of drag-bars having their ends pivoted alternately to one and the other of two rock-bars, whereby they may be thrown 60 from a single into a double rank, a corresponding series of connecting-links pivoted at one end to arms carried by a rock-shaft journaled in the frame of the drill or cultivator, and a pinion journaled in one end of a lever, said 65 pinion having a flange or cylindrical bearing provided with a double notch or slot, a rigid support having a detent engaging with either of said notches, and a connecting-rod, one end of which engages with a crank-pin upon the 70 pinion and the other with an arm upon the rock-shaft, whereby upon actuating the lever the detent is released from the pinion, the latter is caused to mesh with a gear upon the axle, the rock-shaft is turned, and the hoes 75 raised or lowered, the bearing-flange upon the pinion riding upon the detent until the movement is completed in either direction, at which instant the slot automatically engages with said detent, and the pinion is withdrawn by 80 gravity from the gear, thereby locking the parts in the position to which they have been moved.

85 Our invention consists, for the third part, in a driver's seat mounted upon a single rigid support having adjustment longitudinally between parallel supports upon the drill-frame, and a clamping-screw and bolt for locking the seat-support in place thereon.

90 Our invention consists, for the fourth part, in the several novel features of construction, and the combinations and sub-combinations of parts, hereinafter described, and pointed out in the claims.

95 Referring to the drawings forming part of this application, Figure 1 is a plan view of a grain-drill embodying our invention. Fig. 2 is a vertical section taken in the plane 22,

- Fig. 1, the line of sight being indicated by the arrow. Fig. 3 is a vertical section taken in the plane 33, the line of sight being indicated by the arrow. Fig. 4 is a perspective view of the actuating-gear upon the axle, the pinion journaled in a spring-lever, with its notched flange, and the rigid support with its locking detent, together with the bearings by which said devices are supported, the parts being separated for the purpose of illustration. Fig. 5 is a rear elevation of the parts shown in Fig. 4 assembled together. Fig. 6 is a central transverse section of the pinion shown in Figs. 4 and 5. Fig. 7 is a detail perspective of the seat-supporting bar with its locking and adjusting devices, one of which forms the foot-rest for the driver. Fig. 8 is a detail perspective of one of the connecting-links in engagement with its drag-bar.
- 20 A in said drawings indicates the frame in which the operative parts are supported, said frame being of rectangular form, braced in the usual manner, and carried by a single pair of wheels connected by an axle, B, one of said 25 wheels being rigid with and the other loose upon the said axle. At suitable intervals upon the latter are rigidly mounted two gears, B' and B², one actuating the mechanism by which the hoes are shifted from a single to a double 30 rank, and the other operating the devices by which the whole series of hoes is raised from the earth or dropped.
- The drill-boots or hoes C, which are of the usual form, are each rigidly attached to one 35 extremity of a drag-bar, D, having its other end pivotally connected to one or the other of the two rock-bars E E', which are journaled in bearings e e upon the side bars of the frame A, the arrangement being such that each alternate drag-bar throughout the whole series 40 is connected with the rock-bar E and the remainder with the rock-bar E'. These bars which extend from one side bar of the frame to the other, are each provided with a segmental gear, e', mounted upon each end and meshing together, so that if either one is rocked in its bearings the other will by means 45 of said gears have a corresponding movement in the opposite direction. Each bar E and E' 50 is of quadrantal shape in cross-section, and they have their peripheral surfaces placed in juxtaposition, the drag-bars D being pivoted in mountings d, secured to the outer and opposite plane faces. An arm, F, is mounted upon 55 the rock-bar E, to which is pivoted a connecting-rod, G, by the reciprocation of which the rock-bars are oscillated. The operation of the parts described is produced by the following mechanism:
- 60 At the rear of the frame A is a transverse bar, A', upon which, and within convenient reach of the driver, is mounted a lever, H, which, as shown, may approximate the form of a bell-crank, although other forms may answer the purpose. This lever H is pivoted 65 within a bearing, h, having an angle-plate, h' h², which embraces two sides of the bar A', with

perforations to receive attaching-lugs h³ h², between which said lever H is pivoted. (See Figs. 4 and 5.) A leaf-spring, c, (see Fig. 2,) is attached to the bar A', and engages with the horizontal arm of the lever, which is normally thrown down by the action of said spring. Upon the other side of the pivotal point the lever H is curved upward, and its extremity is provided 70 with a foot-treadle, h⁴, which may be depressed by the foot of the operator. At the end of the horizontal arm of said lever is journaled a pinion, I, having a crank-pin, i, to which is connected the end of the rod G. The arrangement of the parts is such that this pinion I is in the same vertical plane with one of the gears, B', mounted upon the axle B, with which it may be caused to mesh by simply pressing upon the treadle h⁴, whereby the pinion will 75 be raised until its teeth engage those of the gear B', when the pinion will be rotated, the connecting-rod G will be reciprocated, and the rock-bars E and E' will be oscillated in opposite directions, thereby imparting to the hoes, 80 through the medium of the drag-bars D, a reciprocating motion in the line of the drills, each alternate hoe moving in the same direction and opposite to the movement of the adjacent hoes. This reciprocation will continue 85 as long as the pinion I is held in engagement with the gear B' on the axle, and the hoes will be thrown into rank and out of rank repeatedly as long as continuous pressure is exerted upon the treadle h⁴. When it is desired, however, to shift the hoes from a single into a double 90 rank and lock them temporarily in that position, or vice versa, we employ, in combination with the mechanism described, the following devices:

Upon the face of the pinion I is formed a horizontal flange, i', having notches or slots i² and i³ cut therein at opposite points. Upon the transverse bar A' is rigidly mounted a supporting-arm, K, having its end projected under the flange i', with a detent, k, formed upon the upper side of the arm, and of such size that it will readily engage with either of the notches i² i³ when the latter are brought by the revolution of the pinion I to register with the detent. The lever H being normally thrown downward by the action of the spring c, it will be seen that when the detent has engaged with either slot in the flange i' it will remain therein, securely locking the pinion I 100 against revolution until by operating the lever H the notched flange is raised from the detent and the pinion meshed with its actuating-gear. By locking the pinion in this manner the rock-bars E and E' will also be locked through 105 the medium of the connecting-rod G, and the hoes therefore will be permanently held either in a single or a double rank, the arrangement depending upon which notch i² or i³ the detent k engages with. Instead of the rock-bars geared together, as described, a single shifting-bar may be used, having each alternate drag-bar attached to it, and the others to a stationary bar, in the usual manner, the same 110

mechanism herein described being used for operating the shifter. When the lever H is actuated in the manner already described, the pinion I, being thrown upward, makes an operative engagement with the axle-gear B' at the moment when the slotted flange i' clears the detent k. If, now, the foot is removed from the treadle h', the flange i' will rest upon and ride over the detent until the pinion has 10 made one-half of a revolution, when the second notch, i'', having reached the locking-tooth, will be thrown into engagement therewith by means of the spring-actuated lever H. The rock-bars E E' being, as well as their gears, 15 of quadrantal shape, or toothed through an arc of ninety degrees, it will be seen that a single half-revolution of the pinion I will throw the hoes from a single into a double rank, or vice versa, while at the same moment that the 20 change is effected the spring-lever H, carrying the pinion, effects the engagement of the slotted flange with the detent, automatically locking the hoes in the arrangement which has been made by the half-revolution of the 25 pinion I. The instant the latter meshes with the axle-gear the foot may be removed from the treadle h', the change in rank and the locking of the hoes in position being accomplished by the automatic mechanism described.

30 When the drill is in operation, a single touch of the foot upon the treadle will be sufficient. In Fig. 3 of the drawings the parts are shown in the act of throwing the hoes from a single into a double rank, the flange i' riding upon the detent k, the notch i'' being upon the point of engaging with said detent.

35 For the purpose of raising the hoes from the ground and locking them temporarily in that position, we have devised a simple and effective mechanism, which is illustrated in Figs. 1 and 3 of the drawings. Above and somewhat in front of the axle B is placed a transverse rock-bar, L, journaled in bearings in the side bars of the frame A. At intervals upon 40 said bar are rigidly mounted arms l. Directly over each drag-bar D, and between the forked extremities of each arm, is pivoted a drop-link, M. (Shown in detail in Fig. 8.) The lower part of each link is slotted longitudinally at m, 45 and through the slot a drag-bar D is passed, a spiral spring, m', encircling the link and resting upon the upper edge of the bar, the tension of said spring being preserved by a collar, m'', against which its end abuts. These 50 springs serve to press the drag-bars down, in addition to their own gravity, and hold the hoes in the soil. Chains may be used for raising the hoes, instead of the links and springs described, the raising mechanism being the 55 same. Upon the rock-shaft L, which carries the drop-links M, hanging from the arms l, is mounted an arm, l', having a connecting-bar, N, pivoted to its extremity, the position of the arm l' being such that the lower end of the 60 bar N may be mounted on a crank-pin, p, which projects from the outer face of a pinion, P, which is journaled in the end of a le-

ver, R, pivoted in bearings h³ h³, similar to those carrying the lever H upon the transverse bar A'. The pinion P and the axle-gear B² 70 are so arranged that upon the former being raised the two will mesh, causing the pitman to revolve, and through the medium of the connecting-bar N throwing the arm l' up or drawing it downward, according to the position of the crank-pin p at the moment the pinion engages with the axle-gear. The rocking of the shaft L sweeps the arms l through a sufficient arc to raise or lower the hoes to the required point. In order to lock the hoes in 80 either position, we employ mechanism similar to that already described in connection with the shifting device. Upon the inner face of the pitman P is formed a flange, f, having opposite notches, f' f'', which engage with a tooth, s, 85 formed upon a rigid support, S, mounted on the bar A' and extending beneath the pinion. The lever R is in all essential respects a duplicate of the lever H, with the exception of the omission of the spring, the gravity of the hoes being sufficient to unmash the pinion and axle-gear and effect the locking of the former, and it is 90 operated in a similar manner. Upon depressing the treadle r² the pinion P is raised, clearing its notched flange from the detent s and 95 causing it to mesh with the axle-gear B². The flange f, riding upon the detent during a half-revolution, engages therewith the moment the movement is completed, and the pinion having in the meantime thrown the arm l' up into 100 the position shown in Fig. 3, the hoes are drawn up by the drop-links M and are locked in that position, the locking and the disengagement of the gear and pinion being automatically effected in the manner described, 105 which is substantially similar to that embodied in the shifting apparatus.

It will be noticed that the mechanism for raising and lowering the hoes is wholly independent of the shifting devices, and either one 110 may be operated without regard to the other; or both might be operated simultaneously should occasion arise; or the two movements may be simultaneous in part only.

As already mentioned, we depend upon 115 gravity to throw down the lever R, which carries the pinion by which the raising and lowering of the hoes is effected. It will be seen by examining Fig. 3 that the weight of the hoes which is sustained by the several drop-links M 120 is in a great measure thrown upon the connecting-rod N, and when the pinion P has revolved through a half-revolution the gravity of the hoes will throw the notched flange into engagement with the detent s, thereby locking 125 the hoes, and at the same moment unmashing the pinion and its axle-gear.

It should also be mentioned that, if desired, the lever H may be weighted sufficiently to insure its automatic action, thereby enabling 130 us to dispense with the spring.

Two or more perforations, m, may be formed in the ends of the drop-links M, whereby the hoes may be adjusted and the depth of the

drills controlled. It should be noted also that although we have shown the levers H and P so constructed as to be operated by the foot, we do not confine ourselves to that form, since either one, or even both, may be constructed in the form of a hand-lever, as shown in dotted lines in Fig. 2.

For the purpose of economizing material and labor, greatly simplifying the construction, and imparting increased strength and efficiency to this apparatus, we apply the mountings carried by the beam A' in the manner following: Upon each of the levers H and P is formed a boss, n, through which the pivot-bolt n' passes. Each lever is mounted between drop bearings or lugs h³ h³, which depend from an angle-plate, h¹ h², the horizontal portion h² of said plate being the longer and having end perforations for the attaching-screws. The supporting-arm K is provided with a vertical plate, a², having a horizontal plate, a³, forming an angle with it corresponding with the angle between the drop-lug h³ and the horizontal plate h². Perforations 1 2 are formed in said plates, the former registering with the openings u' for the pivot-bolt, and the latter with the end perforation in the plate h². The support K being so placed that its plates a² and a³ lie in the angle between the lug h³ and the plate h², the pivot-bolt n' is inserted and its nut turned on, as shown in Fig. 5. Screws are then passed through the end perforations of plate h², one of said screws having also engagement with the plate a³ through the opening 2. It will thus be seen that we are enabled to attach all these several parts with the same number of fastenings used for mounting the lever H only, while at the same time the strength, simplicity, and compactness of the arrangement render it highly advantageous.

It will be noticed that in Fig. 4 a vertical offset or shoulder, a⁴, is formed upon the arm K, which rests against the front edge of the drop-bearing h³, giving an extremely strong support to said arm and taking a considerable portion of the strain or side-thrust off the end of the lever pivot n'.

The driver's seat is mounted upon two central longitudinal and parallel supports, T T, resting upon the cross-beam A' and stepped under the brace B⁴. The seat V is carried upon the end of an oblique rigid bar, V', which is rendered adjustable longitudinally between said supports, or removable therefrom, by the means shown in Fig. 7. Upon the sides of the bar V', near its lower end, and at a suitable angle with the axis of said bar, are formed slots v v, within which the inner faces of the supports T T fit. A strong metal plate, A², having its upper face in the same plane with the lower faces of the slots v v, is secured to the front of the bar, and a similar plate, A³, having its lower face in the plane of the upper edges of the slots, is fastened to the back of the seat-bar. Each plate is extended laterally, so as to have bearing upon

the lower and upper faces, respectively, of the supports T, as shown in Fig. 2. To the forward plate is centrally attached a stud or bolt, b², having a threaded end, over which is fitted a metal strip, C², angled at o o to fit over the supports upon which it is placed, and having lateral extensions D², which serve as foot-rests for the driver.

The parts described being placed in position, as shown in Fig. 2, the seat may be adjusted toward and from the front, moving between the supports T T, and being securely locked in any desired position by turning the thumb-nut t down upon the threaded end of the bolt b² and against the metal strip C². By simply loosening the nut the seat may be adjusted or wholly removed from its supports, if desired, by drawing it out from between the ends of the supports. This adjustment of the seat is desirable, especially when foot-levers are used to actuate the shifting and raising mechanism, since for drivers of different heights the seat should be placed within the most convenient reach of the treadle ends h⁴ of the foot-levers. Instead of using two parallel supports T T, as shown, a single strip or beam may be employed, having its rear end slotted to receive and permit the adjustment of the seat.

Central support is given to the axle B by means of half-bearings D⁴, secured to the lower faces of the seat-supports T T, as seen in Fig. 2. The axle being long and slender, it may be desirable to give it one intermediate support to prevent it from being sprung should the great weight or pressure be accidentally exerted upon the foot-levers. This will also prevent the springing of the seat-supports T, which lie directly above the axle, should the latter be sprung accidentally upward.

Having thus described our invention, what we claim is—

1. In a grain-drill, the combination, with the shifting bar or bars, of a rod connecting said bar or bars with a crank-pin upon a pinion, said pinion being mounted upon a lever, by which it is held out of engagement with the axle-gear, and having a peripheral flange provided with notches which engage with a locking-detent upon a rigid support for said pinion, substantially as described.

2. The combination, with a gear rigid upon the axle, of a lever carrying a pinion having a notched flange and a rigid support beneath said flange, provided with a locking-detent, upon which the notched flange rides when meshed with the axle-gear, and with which it automatically engages when the notch reaches the detent, thereby unmeshing the pinion and gear, substantially as described.

3. The combination, with a series of hoes attached to drag-bars, of a corresponding series of drop-links or their equivalents pivoted to a rock-shaft journaled in the frame, a rod connecting an arm upon said shaft with a crank-pin upon a pinion mounted upon a lever, by which it is held out of engagement

- with the axle-gear, and a rigid support beneath said pinion, having a locking-detent which engages with an oppositely-notched flange on said pinion, substantially as described.
4. The combination, with the pinion mounted upon a lever, and having a peripheral flange with opposite notches formed therein, of a rigid support mounted upon the drill-frame, said support being provided with a detent, substantially as described.
5. The combination, with two independent axle-gears, of two pinions, each mounted upon a pivoted lever and normally held out of mesh with said axle-gears, one of said pinions actuating the bar or bars to shift the hoes, and the other a rock-shaft to raise and lower them, said mechanisms being wholly separate and capable of independent or of simultaneous operation, substantially as described.
6. The combination, with the rock-bars geared together and journaled in the drill-frame, of drag-bars pivoted alternately to each of said hoes, a rod connecting an arm upon one of said bars with a pinion, and a lever carrying said pinion and holding it normally out of mesh with the axle-gear, substantially as described.
7. A locking-pinion for shifting or raising the hoes of a grain-drill, said pinion being provided with a flange having notches at suitable intervals adapted to engage with a locking-detent mounted on the drill-frame, substantially as described.
8. The combination, in a grain-drill, with the drag-bars and the rock shaft or shafts by which they are carried, of mechanism, substantially as described, intermediate between said rock-shaft and the revolving axle, whereby the hoes are shifted by the power of the team, and automatic locking mechanism engaging at intervals with the shifting devices and holding the hoes in or out of rank, substantially as described.
9. In a grain-drill, the combination, with the hoes and their drag-bars, of drop-links pivoted to a rock-shaft, mechanism, substantially as described, connecting the rock-shaft with the revolving axle, and automatic locking devices engaging at intervals with said mechanism, whereby the hoes are raised by the power of the team and automatically locked in position, substantially as described.
10. The combination, in a grain-drill, with the drag-bars and the shifting bar or bars by which they are carried, of mechanism for shifting the hoes into double or single rank or for reciprocating them continuously by the power of the team, and of mechanism for automatically locking them in or out of rank, substantially as described.
11. In a grain-drill, the combination of the hoes and their drag-bars connected by chains or links to a rock-shaft, and mechanism connecting the rock-shaft with the revolving axle, whereby the hoes are raised by the power of the team and automatically locked in position, substantially as described.
12. The combination, with the bar carrying the seat, and having laterally-extending plates in rear and in front, which engage with the parallel seat-supports, of a central vertical bolt projecting between said supports, a perforated plate engaging with said bolt, and a thumb-nut engaging with the threaded end of the latter, substantially as described.
13. A seat having adjustment between horizontal parallel supports, in combination with a locking-plate provided with lateral extensions adapted to serve as foot-rests for the driver, substantially as described.
14. The combination, with the drop-bearings for the pivoted levers, of angle-plates partly embracing a cross-beam of the drill-frame, and a rigid support having an angular attaching portion occupying the angle between one of the drop-bearings and its attaching-plate, registering perforations being formed in each to receive the lever-pivot and attaching-screw, substantially as described.
15. The combination, with the parallel central supporting-beams, of a seat carried by an inclined bar having supporting transverse plates attached to its lower end and resting upon the parallel beams, and adjustable thereon, with a clamping-bolt and nut carried by one of said transverse plates, substantially as described.

In testimony whereof we have hereunto set our hands in the presence of two subscribing witnesses.
